UNITED STATES PATENT OFFICE

CHARLES GILBERT HAWLEY, OF CHICAGO, ILLINOIS, ASSIGNOR TO CENTRIFIX CORPORATION, OF CLEVELAND, OHIO, A CORPORATION OF OHIO

CUPOLA TOP.

Application filed March 11, 1926. Serial No. 94,087.

My invention relates to improvements in foundry cupolas and the like which emit great quantities of dust to the detriment of surrounding neighborhoods and which, in my view, unnecessarily waste great quantities of heat. The object of my invention is to obviate both, and my invention comprises certain elements adapted to be placed at the top of such a stack and which act to conserve the waste heat and the gases emitted by the stack and to prevent the escape of the dust which accompanies the gas.

The invention will be readily understood on reference to the accompanying drawing, in which Fig. 1 is an elevation of a typical foundry cupola with its upper part in section and equipped with apparatus embodying this invention; Fig. 2 is a horizontal section on the line 2—2 of Fig. 1; and Fig. 3 is a horizontal section on the line 3—3 of Fig. 1.

It will presently become apparent that my invention is by no means limited to use upon foundry cupolas but is of a much more extensive utility. But a foundry cupola presents opportunities for accomplishments of both of the objects of the invention and for that reason has been selected for special illustration.

Furthermore, cupolas are usually made much higher than necessary for the sake of the combustion within the cupola and usually with the mere object of sending the gases high enough to prevent the immediate drop of the dust. In contrast where my invention is used, the cupola need be very little higher than called for by the height of the charging floor and the charging door 2. As usual the cupola is arranged on an elevated base and comprises a metal shell 3 that contains a refractory lining 4; the latter extends to the top of the shell, and according to my invention is made to support a waste heat recovering appliance 5. As well shown in Figs. 1 and 2, that appliance comprises a tight blast box 6, arranged on the top of the cupola together with a copper screen S, the edges of which extend into the blast box 6. The blast box is supplied with pressure air through the connection 6', shown in Fig. 3, and the air is therein heated to a high tem-

perature and then by the way of the pipe 7, is conducted to the box or chamber 8 at the bottom of the cupola from which the cupola tuyères are supplied. Insulating material 9 covers the exposed surfaces of the box 6 and the parts 7 and 8. Because of the high conductivity of copper, copper rods are here used for making the screen S. And without interfering with the tightness of the joints in the box 6, (loose joints would involve a loss of pressure air) the whole screen is preferably made so that it may be removed when the door plate 9 is detached from the remainder of the box 6. Most conveniently the screen is not woven but instead there is first a lower course of copper rods S' extending in one direction and preferably corrugated or spiraled to hold an oppositely extending course or layer of straight rods S''. Copper rods of from one-fourth to one-half inch in diameter are used and their ends extend liberally into the space within the box 6. Generally, they may be welded or otherwise sealed in and become permanent with the internal collar 6'' of the blast box 6, but in every case it is believed that the removable section 9 of the blast box will prove a convenience, both during original installation of the screen and at times when repairs are required.

As about to be explained, the dust catcher is erected directly upon the top 6^a of the blast box 6 and that part of the blast box is used for the additional radiation of heat to the air in the box. To supplement the radiating surface, the under side of the ring 6^a is provided with a large number of circumferential fins or ribs 6^b. Briefly, the copper screen readily takes up heat from the hot gases ascending from the cupola and as readily imparts that heat to the air that is moving in the box 6. Furthermore, this abstraction of heat so reduces the temperature of the gases that any flame that may flash or exist in the cupola top is suppressed and does not persist above the screen. This last is a practical prerequisite to the use of a dust catcher composed of metal and positioned at the top of the cupola. Another advantage of the copper screen flows from the character of the metal itself which being tough resists the abrasive wear of the

dust particles that rise with the swiftly moving gases.

Rising from the floor ring 6^a that forms the top of the blast box 6, is a plurality of circular series of tangentially positioned blades 10, between every pair of which is a tangential tuyère 11. Obviously, the member thus erected is of about the same internal diameter as the cupola, in practice only slightly larger, and is of no great weight. At their tops the blades 10 are fastened to a ring 10' and that ring supports a cover plate 10'' which is made preferably of very thin metal to the end that the transmission of any residual heat shall be as little as possible obstructed at that point. Protected by the heat absorbing member 5, the metal parts above it become quite permanent in character.

Under the direction of the members 10 and 10'' the gases rising from the cupola are directed backward against the opposed substantially cylindrical wall 12, which also rises from the plate 6^a. This part 12 therefore receives the impact of the dust particles which are deposited thereon by the whirling movement of the gases and are thus separated from the latter. The gases whirl upwardly toward a large central outlet 13 at the top of the casing 14 which surrounds the member 12.

Thus, the dust which is centrifugally separated against the air casing 12 is conveyed to the top of that member where it whirls out into the top of the encompassing dust pocket 15, while the clear gases depart through the outlet 13. It is of distinct advantage that my invention permits the employment of an outlet 13 that is so much larger than the body of the cupola as to effectively obviate back pressure within the dust catcher. The walls of the dust pocket will be identified in the conical part 16, the vertical wall 17, and the bottom 18, the last may be of any desired shape to facilitate the discharge of the collected dust. Usually several down pipes 19 extend therefrom to one or more dust pockets 20 suspended beneath the charging floor A. That floor having been pointed out the lines B are identified as belonging to the roof of the cupola house.

It is believed the foregoing description will make it clear that such dust as may rise from the cupola with the gases is intercepted by the described dust catcher, second, that the heat of the gases is utilized with great advantage at the base of the cupola, and that third the means employed for absorbing the otherwise waste heat serve to prevent destructively high temperatures within the dust catcher; and all without detrimentally affecting the draft of the cupola or other stack.

Various modifications of my invention will readily suggest themselves to those skilled in the art and it is to be understood that the invention is by no means limited to the precise structures herein shown and described.

Instead the scope of the invention as well as its essential details are to be ascertained from the appended claims as read in the light of the foregoing description.

Having thus described my invention I claim as new and desire to secure by Letters Patent:

1. A stack for hot gases, in combination with a heat absorbing and dispersing screen extending transversely of said stack, heat conserving means for accepting the heat from said screen, and a dust catcher positioned above and defended by said screen. 75

2. A stack, in combination with a heat absorbing screen at the top thereof, a blast box there positioned to accept the heat from said screen, and means for supplying air to said box and also for conducting the heated air from said box. 80

In testimony whereof I have hereunto set my hand this 9th day of March, A. D. 1926.

CHARLES GILBERT HAWLEY.
